BASKETBALL GAME BOARD

Kazuyuki Hashimoto, Tokyo, Japan, assignor to Toytown
Corporation, Tokyo, Japan

Filed Sept. 25, 1973, Ser. No. 400,660

Term of patent 14 years

Int. Cl. D21—01

U.S. Cl. D34—5 SS

FIG. 1

FIG. 2

FIG. 3

FIG. 4

FIG. 1 is a perspective view of a basketball game board, embodying my new design;

FIG. 2 is a right side elevational view thereof;

FIG. 3 is a front elevational view thereof; and

FIG. 4 is a top plan view thereof.

The right and left side elevational views and the front and rear elevational views are identical while the bottom is flat.

I claim:

The ornamental design for a basketball game board, as shown and described.
